UNITED STATES PATENT OFFICE.

LEE DE FOREST, OF NEW YORK, N. Y., ASSIGNOR TO DE FOREST RADIO TELEPHONE CO., A CORPORATION OF NEW YORK.

TRANSMISSION OF MUSIC BY ELECTROMAGNETIC WAVES.

1,025,908.

Specification of Letters Patent.

Patented May 7, 1912.

Application filed March 9, 1907. Serial No. 361,478.

To all whom it may concern:

Be it known that I, LEE DE FOREST, a citizen of the United States, and a resident of New York, in the county of New York and 5 State of New York, have invented a new and useful Improvement in Transmission of Music by Electromagnetic Waves, of which the following is a specification.

My invention relates to the transmission 10 of music by means of electromagnetic waves without the use of connecting wires between the transmitting and receiving systems.

The object of my invention is to produce a system whereby musical sounds may be 15 developed and transmitted by electromagnetic waves at a central distributing point to one or more receiving stations.

My invention will be described in connection with the drawings which accompany 20 and form a part of this specification and which illustrate two arrangements of apparatus and circuits whereby the foregoing objects have been successfully realized in practice; but it is to be understood that many modifications may be 25 made in the particular embodiments of my invention which I herein show and specifically describe without departing from the principle of said invention.

30 In the drawings, Figure 1 represents one embodiment of the present invention wherein a source of practically-continuous or undamped electrical vibrations is employed, Fig. 2 represents a modification in which the 35 oscillations developed in a sonorous circuit have a spark-frequency comparable with the frequency of the highest note employed in music. Fig. 3 diagrammatically represents a receiving system.

40 In the figures, V is an elevated conductor. M M' M'' M''' are transformers, of which the primaries and secondaries, respectively, are I₁ I₁', &c., and I₂ I₂'.

45 R R are impedances.

C C' are condensers.

D is a source of unidirectional electro-motive force.

50 A A' A'' A''' are sources of vibratory electro-motive force.

K K' K'' K''' are circuit closers.

The circuit S' C I₁ is an oscillatory circuit provided with electrodes between which an electric arc may be developed at S' when the source D is connected to the terminals of said 55 electrodes. The impedances R R connected

between the source D and the arc-electrodes prevent any sudden change of current value in the supply circuit and under these conditions, as is now well understood, practically-continuous or undamped electrical oscillations will be developed in the circuit S' C I₁, the energy of which by the transformer M or by other suitable means may be conveyed to the elevated conductor system V I₂ E and converted into electro-radiant energy.

Operatively associated in any suitable way with the source of practically-continuous or undamped electrical oscillations is means for modifying the electrical vibrations in accordance with the musical sounds to be transmitted. The particular means for so modifying said electrical vibrations which I have illustrated in Fig. 1 for the purpose of more fully disclosing the present invention is a 75 circuit containing means for developing vibratory electric currents varying in accordance with the sounds to be transmitted and the particular means shown in said figure whereby said circuit is associated with said 80 source of oscillations is the transformer M'' provided with the iron core H. The aforesaid circuit is operatively connected with a number of sources of vibratory electric current, A A'' A''' which may be alternating 85 current generators which, preferably, develop simple harmonic currents each having a frequency corresponding to the frequency of one of the notes of the musical scale. By means of the circuit closers K' K'' K''' said generators may be simultaneously 90 or otherwise connected in series with the primary winding I₁'' of the transformer M'' and the energy of the currents developed by said generators will modify 95 the oscillations developed by the circuit S' C I₁ in the elevated conductor system will be correspondingly modified and the electromagnetic waves radiated from said system 100 will have the same characteristics as to frequency and amplitude as the oscillations in said system.

In the system shown in Fig. 2 the circuit S' C I₁ is a sonorous circuit energized by the alternator A or other suitable source of vibratory currents adapted to produce in 110 the circuit S' C I₁ electrical oscillations hav-

ing a spark-frequency comparable with the frequency or rate of vibration of the highest note employed in music. The circuit which includes the primary I_1''' of the transformer 5 M''' may, as shown, be associated directly with said sonorous circuit which will under the circumstances include the secondary I_2''' of said transformer. The transformer M''' is of the air-core type. It will be under-
10 stood without further illustration that the circuit including the generators A' , &c., may be associated with the circuit $S C I_1$ in the same manner as shown in Fig. 1, and that it may be associated with the circuit $S' C I_1$
15 in the same manner as shown in Fig. 2. The condenser C' may be employed as shown in Fig. 1 to shunt the impedance of the generator D with respect to the vibratory currents developed in the secondary of the
20 transformer M''' .

The electromagnetic waves developed by the systems shown in Figs. 1 and 2 and which, although exceeding in frequency the limit of audibility, are modified in ampli-
25 tude by vibrations corresponding to the sonorous vibrations of the air accompanying the musical sounds to be transmitted, may be received and their energy converted into vibrations of the air corresponding to
30 the original musical sounds by means of any suitable receiving system. At such receiving system the energy of the electrical oscillations resulting from the waves received will be converted by means of a wave detec-
35 tor into local circuit currents modified in accordance with the currents produced in the primary circuits of the transformers M'' and M''' . The local circuit currents may be translated by a telephone receiver
40 which may be connected to said local circuit with or without the interposition of a relay, such, for example as that shown in my Letters Patent No. 841,387, dated January 15,
45 1907. Such a receiving system by way of illustration is shown in Fig. 3 in which $V_1 I_1^{iv} E$ is the elevated receiving conductor system with which may be associated the tuned receiving circuit $I_2^{iv} C^{iv}$. F is a wave detector herein shown as an audion, $B B'$
50 are batteries and T is a telephone receiver.

I claim:

1. The method of transmitting musical sounds which consists in developing elec-

trical vibrations having a frequency higher than the limit of audibility, and generating 55 respectively independent electric currents corresponding in frequency to simple harmonic sound waves, successively modifying the electrical vibrations by said independently generated currents, and transforming 60 the modified electrical oscillations into electro-radiant energy.

2. In a system for transmitting musical sounds, an oscillating circuit, means for producing therein practically continuous electrical vibrations having a frequency higher than the limit of audibility, a modifying circuit associated with said oscillating circuit, a plurality of means arranged in the modifying circuit respectively operating to 70 develop therein electric currents, and means for varying each of said electric currents in accordance with the sound vibrations of a different musical note.

3. In a system for transmitting musical 75 sounds, an oscillating circuit, means for producing therein practically continuous electrical vibrations having a frequency higher than the limit of audibility, a modifying circuit associated with said oscillating circuit, a plurality of means arranged in the modifying circuit and respectively operating 80 to develop therein electric currents, means for varying each of said electric currents in accordance with the sound vibrations of a different musical note, and a transformer associating said modifying and oscillating circuits, said transformer having an iron core.

4. In a system for transmitting sounds, 90 an oscillating circuit, means for producing therein electrical vibrations having a high frequency, a modifying circuit associated therewith, and means respectively independent of each other, and arranged in the 95 modifying circuit for respectively varying the current therein in accordance with each note of the harmonic scale.

In testimony whereof, I have hereunto subscribed my name this 6th day of March 100 1907.

LEE DE FOREST.
